UNITED STATES PATENT OFFICE.

ROWLAND W. MILLER, OF WILLIAMSTOWN, WEST VIRGINIA

ACETYLENE-GAS GENERATOR.

Application filed October 17, 1921. Serial No. 508,070.

To all whom it may concern:

Be it known that I, ROWLAND W. MILLER, a citizen of the United States, and a resident of Williamstown, in the county of Wood and State of West Virginia, have invented certain new and useful Improvements in Acetylene-Gas Generators, of which the following is a specification.

My present invention relates generally to acetylene gas generators and more particularly to portable apparatus of this nature, my object being the provision of a simple, strong and durable apparatus by means of which gas may be continuously generated, uniform in quantity, pressure and quality. Certain other objects relate specifically to different portions of the generator as for instance the means proposed for the feed and control of carbide and the automatic means provided to regulate this feed as well as the means employed to clean gas and certain other mechanical features to which I will hereinafter specifically refer in connection with the accompanying drawings.

In these drawings which illustrate several parts of my invention and which form a part of this specification,

Figure 1 is a perspective view of the complete apparatus,

Figure 2 is a top plan view thereof,

Figure 3 is an enlarged vertical longitudinal section through the gas filtering device;

Figure 4 is a vertical transverse section through the device shown in Figure 3.

Figure 5 is an enlarged vertical section through the upper portion of the apparatus of Figures 1 and 2.

Figure 6 is a detail vertical section taken substantially on line 6-6 of Figure 5,

Figure 7 is a perspective view of the automatic pressure controlled regulator.

Figure 8 is a vertical section through portions of the regulator shown in Figure 7, and

Figure 9 is a detail horizontal section taken on line 9-9 of Figure 8.

Referring now to these figures and particularly to Figures 1, 2 and 5, I preferably utilize a vertical cylindrical water tank 10 whose interior, above its water line, forms a gas generating chamber 11 as seen in Figure 5, the tank receiving carbide through an upper central opening 12 around which is secured the base of an upright valve casing 13. This valve casing is in-

tegral at one side with the lower laterally opening end of a feed elbow 14 into whose laterally offset and upwardly opening end is threaded the lower reduced end of the carbide hopper 15 from which the carbide freely flows into the feed elbow 14 outwardly beyond a depending baffle 16 located within the elbow at a point spaced from its inner end communicating with the valve 85 casing 13.

One side wall of the valve casing 13 as well as a portion of the wall of the feed elbow 14 support bearings 17, preferably adjustable as shown, for a rotatable shaft 70 18 which extends axially through the lower horizontal portion of elbow 14 and diametrically through the upper portion of valve casing 13 and upon which shaft a valve disk 19 is freely movable so as to slide toward 75 and away from the lower inner end of the feed elbow which extends into the valve casing so as to form a seat for the valve disk when the latter is closed to cut off the feed of carbide downwardly through the valve 80 casing and into the water holder or casing 10. At one end, projecting beyond the valve casing, shaft 18 has a gear wheel 20, and within the lower inner portion of the elbow 14 this shaft has secured thereon a carbide feed member 85 consisting of a pair of helically curved feed arms 21 oppositely disposed with respect to one another, and each gradually tapering to a relatively sharp point 22 so as to dig into the carbide. The ability of these arms to dig into the carbide while shaft 18 is rotating, in conjunction with the baffle wall 16 depending in the elbow to such an extent as to avoid carbide above the rotating feed member 90 between the baffle wall and the inner discharge end of the elbow, obviates all danger of clogging of the feed and permits of rotation of shaft 18 for feed purposes, with minimum power.

The water tank or casing 10 has a valved filling device as at 23 in Figure 1 and a drain at 24 and is provided with an overflow tube 25 for the water having a controlling valve 26 and with gas test tubes 27 having a controlling valve 28, gas flowing upwardly from the generating chamber 11 through a gas outlet pipe 29 having a valve 30 therein and leading to one side of the casing 31 of a pressure regulator below the diaphragm 32 of said casing 31 as particularly shown in Figure 8. This diaphragm is acted upon

by a spring 33 in the casing 31 which tends to force the diaphragm downwardly and controls a valve 34 to which the diaphragm is connected by a stem 35. Valve 34 is disposed in a gas channel 36, between valve seats 37 and 38 which respectively open into the regulator pipes 39 and 40, the parts being so arranged that with normal pressure through the outlet pipe 29 below the diaphragm 32, valve 34 will be held as shown in Figure 8 free of both of the valve seats 37 and 38 and thus gas will pass through both of the regulator pipes 39 and 40. When pressure falls below the desired point, spring 33 will act to depress the diaphragm and thus lower valve 34 onto the lowermost seat 37, cutting off the flow of gas through the regulator pipe 39 and deflecting all of the gas through the regulator pipe 40. On the other hand should the pressure increase above the desired point this pressure will cause upward flexing movement of the diaphragm 32 against the tension of its spring 33 and will seat valve 34 against the upper seat 38 so as to cut off the flow of gas through the regulator pipe 40 and force the gas to pass solely through the pipe 39.

On the water casing 10 at one side of the valve casing 13 beyond the gear 20 of shaft 18 is mounted an upright filter casing 41 whose lower enlarged portion forms a chamber for a rotor 42 having concavo-convex peripheral blades 43 acted upon by the gas rising through water 44 in the filter casing from the lower end of the regulator pipe 40 which enters the lower portion of the filter casing and is in communication with a channel 40^a opening below the rotor, which channel may receive a drain cock 40^b as best seen in Figure 3. This filter casing has a groove in one side wall forming a gas by-pass channel 45 with the lower end of which the regulator pipe 39 communicates. The upper end of this groove or channel terminates above the level of the water 44 which is supplied to the casing through a valved filling device 46, the level being determined by a valved overflow cock 47.

The shaft 48 of the gas actuator rotor 42 extends laterally through the inner wall of the filter casing 41 as shown in Figure 4 and is provided with a small gear wheel 49 in mesh with the gear 20 of the feed shaft 18 so that as the gas passes upwardly in the filter casing from the lower communicating end of pipe 40, the rotor 42 will be rotated and such rotation will be communicated through the gears 49 and 20 to the feed shaft 18.

In the upper portion of the filter casing is a vertically inclined wall 50 above which and between the same and the top of the casing from which the valve gas service connection 51 leads, is packed mineral or other filtering material 52, the inclined partition

or wall 50 having adjacent to its upper end an opening 53 through which the gas passes downwardly beneath a baffle plate 54 carried by and spaced from this partition or wall, causing the gas to thus take a tortuous path and finally emerge from beneath the baffle plate 54 at a point where it will be forced to pass through the full body of the filtering material 52 before finally passing outwardly through the service valve 51.

The carbide feed valve 19 is engaged within the valve casing 13 by the upper yoke shaped end of an arm 55 as seen particularly in Figure 5, the lower end of this arm being secured upon a short shaft 56 which projects outwardly through the wall of the valve casing and has secured thereto the lower end of a lever 57 shown in Figures 2 and 6. This lever is engaged upon the exterior of the valve casing 13 by one hook end of an adjusting screw 58, extending through an outstanding lug 59 of the valve casing and provided with a threaded adjusting nut 60 so that the valve 19 may thus be held in fully closed position against the inner end of the elbow 14 while the generator is being transported from place to place.

In addition to the above described parts which render the generator proposed by my invention of a compact, strong and durable nature as a whole, adapting the same to ready portability, the tank 10 may have a tube 61 secured diametrically therethrough for the reception of a bar to be utilized as a handle so that two persons, one upon each side of the generator may readily carry the same from place to place.

In operation, the opening of the valve 19 and of the gas outlet valve 30, permits of the formation and passage of gas through the gas outlet pipe 39 and into the regulator casing 31. At this time the diaphragm 32 will be in lowered position with the valve 34 cutting off the passage of gas to the regulator pipe 39. Thus all of the gas will be forced to pass through pipe 40 and upwardly around the rotor 42 so as to start rotation of the latter. Immediately upon the start of rotation of the rotor the feed of carbide downwardly through the valve casing will take place by virtue of the rotation of the feed member and the normal operation will then begin. When pressure of gas is built up sufficiently the regulator diaphragm 32 will be elevated and part of the gas will flow through the by-pass channel 45 as previously described and when there is an overflow supply of gas at any time pressure will seat the valve 34 so as to close the pipe 40 leaving all of the gas to flow for the time being and until the pressure again drops to normal, through the by-pass channel 45.

By the above described construction I provide an acetylene gas generator which will

be safe, strong and durable and will at the same time be compact and readily portable, especially adapting the same to garage and service station uses as well as other uses 5 where acetylene gas in small steady quantities is desired.

I claim:

1. In a gas generator, a fluid casing having an upper carbide intake, a valve casing secured over the intake, a carbide container, a feed elbow having vertical and horizontal portions, the vertical portion of which supports said container and the horizontal portion of which opens laterally into the valve casing and has an annular lip projecting inwardly beyond the walls of said valve casing forming a valve seat, and an internal baffle member across its upper portion and spaced from the valve casing, a valve in the valve casing shiftable toward and away from said seat and adapted to control the flow of carbide from the elbow, a shaft extending through the valve casing and axially through the horizontal portion of the feed elbow and upon which said valve is loosely guided and movable, and a feed member secured on and rotatable with said shaft in the feed elbow between the said baffle member and the valve casing, said feed member consisting of a pair of feed arms, rigid at one end with the shaft at diametrically opposite points, each of said arms being spirally curved around one half of the circumference of the shaft in spaced relation thereto and tapering throughout its length 50 to a sharp digging point diametrically opposite to its end connected to the shaft.
2. In a gas generator, a fluid casing having an upper carbide intake, a valve casing secured over the intake, a carbide container, a feed elbow having vertical and horizontal portions, the vertical portion of which supports said container and the horizontal portion of which opens laterally into the valve casing and has an annular lip projecting 40 inwardly beyond the wall of said valve casing forming a valve seat, and an internal baffle member across its upper portion and spaced from the valve casing, a valve in the valve casing shiftable toward and away 45 from said seat and adapted to control the flow of carbide from the elbow, a shaft extending through the valve casing and axially through the horizontal portion of the feed elbow and upon which said valve is loosely 50 guided and movable, and a feed member secured on and rotatable with said shaft in the feed elbow between the said baffle member and the valve casing, said feed member consisting of a pair of feed arms, rigid at 55 one end with the shaft at diametrically opposite points, each of said arms being spirally curved around one half of the circumference of the shaft in spaced relation thereto and tapering throughout its length 60 to a sharp digging point diametrically opposite to its end connected to the shaft.

ROWLAND W. MILLER.
